PORTABLE BURGLAR ALARM

Charles E. Young, Kansas City, Mo.

Application April 3, 1942, Serial No. 437,551

1 Claim. (Cl. 200—52)

1

My invention relates to portable burglar alarms and my object is to provide an electric alarm system which can be applied to automobiles and various other mobile objects for the purpose of giving an alarm when the object is tampered with or moved by an unauthorized person, thus notifying persons within hearing of the alarm that a theft is being perpetrated.

The invention includes a normally open alarm circuit and a normally closed main circuit including a relay for automatically closing said alarm circuit. A resistance normally reduces the strength of the current flowing through the main circuit and the relay below that required to close the alarm circuit. A shunt circuit is provided to short circuit the resistance so that the strength of the current in the main circuit will be increased sufficiently to cause the relay to close the alarm circuit. The shunt circuit is automatically controlled by a pendulum and two oppositely disposed contacts which are incorporated in the shunt circuit. Normally the pendulum is held out of engagement with the two adjacent contacts by the force of gravity, but when disturbed will gravitate into engagement with one or the other of said contacts and close the shunt circuit, thus resulting in short circuiting the resistance and increasing the E. M. F. of the main current sufficiently to cause the relay to close the alarm circuit. As the contacts may engage only momentarily means are provided for keeping the alarm circuit closed so that the alarm will continue to sound until turned off by an authorized person.

In the accompanying drawing which shows a diagram of the invention there is shown a normally closed main circuit comprising wires 2 and 4; a battery or other source of electrical energy 6; a relay comprising an electromagnet 8 in series with the wires 2 and 4; a resistance 12 in series with the main wires 2 and 4, and a manual switch 14 connected to the main wire 2.

An armature 15 adjacent to the core of the electromagnet 8, automatically controls a normally open alarm circuit which includes the armature 15; a battery 16 or other suitable source of electricity; a wire 18 leading from the armature 15 to the battery 16; a manual switch 20 connected to the wire 18 and adapted to open or close the alarm circuit; a wire 22 leading from the battery 16 to a switch 24; contacts 25 and 26 spaced apart and the former of which is connected to an electric bell 27, or other audible signal, and a wire 29 leading from the bell 27 to a conductor 30 equipped with contacts 31 and

2

32 spaced below and above respective sides of the free end of the armature 15. The alarm circuit also includes a branch 34 extending around the bell 27 and connected at one end to the contact 26 and at its other end to the wire 29. A visual signal preferably in the form of a lamp 36, is in series with the branch circuit 34. The bell circuit and the lamp circuit may be opened or closed by the switch 24 which can be in the form of a single pole switch as shown for independently opening and closing either circuit, or it may be in the form of a conventional double pole switch for simultaneously opening or closing the bell and lamp circuits. If desired either the bell 27 or the branch circuit 34 can be dispensed with.

The armature 15 is normally held out of engagement with the contacts 31 and 32 by a spring 40 secured to an insulated part of the electromagnet 8 and provided with a set screw 42 which bears against the free end of the spring 40 and provides a means for adjusting the armature relative to the contacts 31 and 32.

Should either of the main wires 2 or 4 become broken from any cause the electromagnet 8 will become completely deenergized and permit a spring 41 to pull the armature 15 against the contact 32 to close the alarm circuit. The spring 41 is connected at its ends to respective eye-bolts 41a and 41b, which latter extends through the armature and is provided with a nut 41c whereby the eye bolt 41c can be adjusted up or down to regulate the tension of the spring 41. The resistance 12 is arranged to be short circuited by a shunt circuit comprising wires 43 and 44 connected to opposite ends of the resistance and one of which leads to a pendulum 46 and the other to a vertical conductor 47 provided at its lower end with a contact 48. The shunt circuit also includes a wire 50 connected at its respective ends to the conductor 47 and a vertical conductor 51 provided at its lower end with a contact 52. The conductors 47 and 51 are insulated at their upper portions from and disposed at opposite sides of the intervening pendulum 46 which is provided at its opposite sides with contacts 54 and 55 arranged opposite the contacts 48 and 52, respectively.

The pendulum 46 and the respective conductors 47 and 51 each consists preferably of a thin piece of resilient conductive material and the pendulum is provided at its lower portion with an adjustable counterweight 56 secured at any point of its adjustment upon the pendulum by a set screw 58. By forming the pendulum 46 and

the conductors 47 and 51 of resilient material they may yield and avoid damage to the contacts 48, 52, 54 and 55 in the event that the pendulum should be swung violently to either side. The contacts 53 and 52 are held in spaced relation to the contacts 54 and 55 by set screws 60 and 62 threaded in a support and having swivel connections with the conductors 47 and 51, respectively, so that the contacts 48 and 52 may be adjusted towards or away from the respective intervening contacts 54 and 55. Any suitable support may be employed. In the present instance it consists of a standard 64, a vertical arm 66, spacing members 68 and 70 and insulation 72, all of which are clamped together with bolts 74 insulated from the conductors 47 and 51 and the pendulum 46. In addition to the insulation 72, other insulation is employed where needed.

The standard 64 is secured at its lower end upon a base member 76 mounted at one end on a rockable element 78 and provided at its other end with a set screw 80 whereby it may be adjusted to a level position determined by a suitable indicator consisting in the present instance of a freely mounted pointer 82 and an index mark 84. The level indicator may be observed through a small window 85 in a burglar-proof casing 86 fixed upon the base member 76 to protect the pendulum 46, the associated contacts 48, 52, the resistance 12 and the shunt circuit wires against tampering by unauthorized persons.

The main circuit wires 2 and 4 may be of any length, so that the casing 86 and parts associated therewith can be placed a considerable distance from the alarm circuit. For instance, the casing 86 can be placed in an automobile stored in a garage while the alarm circuit can be located in the home to notify the owner if an attempt is made to steal the automobile, or if a wheel is being jacked up for the purpose of removing a tire therefrom. Preferably the main circuit wires 2 and 4 are either armored or concealed. However, if either one or both are cut the electromagnet 8 will become completely deenergized and permit spring 41 to pull the armature 15 against contact 32 and thus close the burglar alarm circuit.

Assuming that the switches 14 and 20 are closed and switch 24 is in engagement with contact 25, and that the base member 76, with associated parts, is placed on a mobile object, it is evident that in the event the latter is moved and causes said base member to incline towards its left end, the pendulum 46 will gravitate into engagement with the contact 48 and close the shunt circuit through wire 43, conductor 47, contact 48, pendulum 46 and wire 44 and thereby short circuit the resistance 12. Thus the strength of the current flowing through the electromagnet 8 is increased sufficiently to overcome spring 40 and attract the armature 15 against contact 31.

thereby closing the burglar alarm circuit through armature 15, wire 18, switch 20, wire 22, switch 24, contact 25, bell 27, wire 29, conductor 30 and contact 31. In the event that the base member 76 should be restored to a level position and allow the pendulum 46 to move out of engagement with the contact 48, the weakened current flowing through the electromagnet 8 will still suffice to maintain the alarm circuit in closed condition owing to the close proximity of the armature 15 to the core of the electromagnet 8. The alarm circuit remains closed until the switch 14, or 20 is opened. Should the base member 76 become tilted to the right the pendulum will gravitate into engagement with contact 52 and close the shunt circuit through wires 43 and 50, conductor 51, contact 52, pendulum 46 and wire 44, thus resulting in the short circuiting of the resistance 12 and closing of the alarm circuit.

It has already been stated how the spring 41 will effect closing of the alarm circuit, and how the light circuit 34 may be closed when desired.

From the foregoing it is apparent that I have provided a burglar alarm which is well adapted for the purpose intended, and while I have shown a preferred arrangement of my alarm system, I reserve all rights to such changes and modifications thereon as properly fall within the scope of the invention, as claimed.

Having thus described my invention, what I claim and desire to secure by Letters Patent, is:

In a portable burglar alarm, a pair of resilient spaced vertical conductors arranged adjacent to each other, a vertically disposed resilient pendulum suspended between but out of engagement with said conductors, supporting means including a standard arranged adjacent to one of the conductors and a vertical arm disposed adjacent to the other conductor, insulated means interposed between the upper portions of the conductors and the pendulum and between the standard and the arm, means for rigidly clamping the upper portions of the foregoing elements together, means carried by the standard and the arm and having a swivel connection with each conductor for adjusting the lower portions of the latter toward or away from the pendulum, and means for normally retaining the standard and the arm in vertical position to normally maintain the pendulum in neutral position, said pendulum being adapted to gravitate and carry one of its contacts into engagement with one of the other contacts and close an alarm circuit if the standard is tilted in one direction or, gravitate in an opposite direction and carry its other contact into engagement with the companion contact and close the alarm circuit if the standard is tilted in a reverse direction.

CHARLES E. YOUNG.
